UNITED STATES PATENT OFFICE.

MICHAEL KIRNBAUER, OF FOREST PARK, ILLINOIS.

ROTARY SLICING MACHINE.

Application filed June 3, 1922. Serial No. 565,609.

To all whom it may concern:

Be it known that I, MICHAEL KIRNBAUER, a citizen of the Republic of Austria (who has declared his intention of becoming a 5 citizen of the United States of America), residing at Forest Park, in the county of Cook and State of Illinois, have invented a certain new and useful Improvement in Rotary Slicing Machines, of which the following is a specification.

This invention relates to that class of culinary slicing machines in which a cutter carrying head having revolution in a horizontal plane, is disposed beneath a stationary open bottom holding hopper adapted to contain the articles or material to be sliced, and the present improvement has for its object:—

To provide a structural formation and 20 association of parts, in which a ready detachment of the different portions of the machine for cleaning and repair is attained, and with which the cutter carrying head is effectively housed against accident, with 25 ready accessibility for adjustment of the cutter blades and for the removal of any obstructing material which may become clogged in the throats or passages in the cutter head through which the sliced material passes downwardly into a receiving 30 bowl or the like. All as will hereinafter more fully appear.

In the accompanying drawings:—

Fig. 1, is a top view of the machine. 35 Fig. 2, is a longitudinal section on line 2—2 Fig. 1.

Fig. 3, is a horizontal section on line 3—3 Fig. 2.

Fig. 4, is a detail vertical section on line 40 4—4 Fig. 3.

Fig. 5, is an enlarged detail transverse section on line 5—5 Fig. 3, of the detachable connection between the hopper base and the bed plate of the machine.

45 Like reference numerals indicate like parts in the several views.

Referring to the drawings, 1 designates the base or bed plate of the machine, having supporting feet 2 by which it is supported 50 above a receiving bowl or the like for the sliced material as it comes from the machine.

The bed plate is provided with a centrally arranged opening 3, in which is arranged the rotary cutter carrying head now to be described.

45 designates a flat circular disk or head

revolvably mounted in the opening 3 aforesaid, by means of a centrally depending shaft having bearing in a horizontal bracket frame 5 and carrying at its lower end a bevel gear wheel 6.

7 designates a horizontal driving shaft journalled in the bracket frame 5 and carrying on its inner end a bevel gear wheel 8 having driving engagement with the aforesaid gear wheel 6 of the cutter carrying head 4. The outer end of the shaft 7 extends beyond the base plate 1 and is provided with a hand crank 9 or other usual driving connection.

10 designates a plurality of track rollers, the carrying frames of which are attached to the base plate 1 near the margin of the opening 2 thereof, with said rollers adapted to have bearing against the under face of the 75 cutter carrying head 4 to support the same against any side sag in actual use of the machine.

11 designates a pair of passages in the head or disk 4, extending radially from near 80 the center to near the periphery of the disk, and providing outlets for the downward passage of the sliced material in the operation of the machine.

12 designates cutter blades preferably of 85 the curved edge type shown in Fig. 4, and arranged at the rear margins of the passages 11 aforesaid. Said cutter blades are preferably of the adjustable type described in my prior Patent No. 1,415,449 dated May 9, 90 1922 with each having a detail association of parts as follows:—

13 designates rock shafts journalled at their respective ends near the respective end of the passages 11 and at the rear sides of 95 the same. The outer ends of the shafts have operative connection with vertical adjusting stems 14 journalled in the marginal portion of the cutter carrying head 4, and by means by which a turning adjustment is imparted 100 to the shaft as set forth in detail in my aforesaid patent. Lengthwise of the shafts 13, the butt portions of the cutter blades 12 are fixedly secured so that each cutter blade 12 will have adjustment in unison with its rock 105 shaft 13.

In the preferred construction shown in Fig. 4, the respective passages 11 are provided with throats 15 extending rearwardly from the shafts 13 and cutter blades 12 aforesaid, with said throats having open bottoms 110 and inclined top walls 16, by means of which

- the sliced material from said cutter blades are directed downwardly in an effective manner and liability to clogging of the throats and passages prevented.
- 5 17 designates a circular wall, the lower end of which carries a plurality of positioning pins 18 adapted to engage in orifices formed therefor in the base plate 1, to afford a readily detachable connection of the wall
- 10 17 to the base plate 1 and at the same time secure said wall in proper concentric relation to the cutter carrying head 4.
- 15 19 designates the holding hopper for the material to be sliced, and which in the present improvement is of a semi-circular form in horizontal section, and arranged to one side of the center of the cutter carrying head 4 in superimposed relation to one-half of said head as illustrated in Figs. 1 to 5 inclusive.
- 20 20 The hopper 19 is open at top and bottom and is supported in the described position by attachment to a fixed semi-circular top plate 20, of the circular wall 17 aforesaid with the lower end of the hopper depending into
- 25 adjacent relation to the cutter carrying head 4 as shown.
- 21 21 designates a pair of quadrant shape cover plates pivoted to the aforesaid fixed top plate 20 and adapted to complete the top closure of the circular chamber formed above the cutter carrying head 4 by the wall 18, and at the same time permit of ready access to said cutter head and associated parts for inspection, adjustment and cleaning.
- 30 In other particulars than above set forth, the hopper 19, with its means for feeding the material to the cutter blades 12, are of substantially the same construction and arrangement as that described in my application for patent, Serial No. 561,269, filed May 16th, 1922, and comprising parts and features as follows:
- 35 22 designates an angle bracket secured to an upper side of the hopper 19, providing pivotal attachment for a cross-head 23 adapted to have movement across the top of the hopper and be secured in a central position above the same by a latch piece 24.
- 40 25 designates a weighted follower head having movement in the hopper 19, and adapted to press the material in the hopper in a downward direction against the cutter blades 12. Said follower head has an upwardly extending guide stem 26, preferably of a rectangular shell form as shown, and having sliding movement in a central guide sleeve 27 on the cross head 23 aforesaid.
- 45 28 designates a cord or like flexible connection, passing over a pulley 29 on the cross-head 23, and down through the hollow guide stem 26 for fixed connection to the follower head 25. The other end of said cord 28 is attached to a lever or arm arranged as follows:—
- 50 30 designates a lever or arm pivoted at the end of the cross head 23 beyond its point of pivotal attachment to the bracket 22 aforesaid, and 31 designates a stop flange or rib on the cross-head, adapted to stop and hold the lever 30 and its connections from further movement when the follower head 25 has reached a predetermined distance above the cutter carrying head 4, in order to prevent contact between and injury to the parts.
- 55 30 designates a lever or arm pivoted at the end of the cross head 23 beyond its point of pivotal attachment to the bracket 22 aforesaid, and 31 designates a stop flange or rib on the cross-head, adapted to stop and hold the lever 30 and its connections from further movement when the follower head 25 has reached a predetermined distance above the cutter carrying head 4, in order to prevent contact between and injury to the parts.
- 60 30 designates a lever or arm pivoted at the end of the cross head 23 beyond its point of pivotal attachment to the bracket 22 aforesaid, and 31 designates a stop flange or rib on the cross-head, adapted to stop and hold the lever 30 and its connections from further movement when the follower head 25 has reached a predetermined distance above the cutter carrying head 4, in order to prevent contact between and injury to the parts.
- 65 30 designates a lever or arm pivoted at the end of the cross head 23 beyond its point of pivotal attachment to the bracket 22 aforesaid, and 31 designates a stop flange or rib on the cross-head, adapted to stop and hold the lever 30 and its connections from further movement when the follower head 25 has reached a predetermined distance above the cutter carrying head 4, in order to prevent contact between and injury to the parts.
- 70 30 designates a lever or arm pivoted at the end of the cross head 23 beyond its point of pivotal attachment to the bracket 22 aforesaid, and 31 designates a stop flange or rib on the cross-head, adapted to stop and hold the lever 30 and its connections from further movement when the follower head 25 has reached a predetermined distance above the cutter carrying head 4, in order to prevent contact between and injury to the parts.
- 75 30 designates a lever or arm pivoted at the end of the cross head 23 beyond its point of pivotal attachment to the bracket 22 aforesaid, and 31 designates a stop flange or rib on the cross-head, adapted to stop and hold the lever 30 and its connections from further movement when the follower head 25 has reached a predetermined distance above the cutter carrying head 4, in order to prevent contact between and injury to the parts.
- 80 30 designates a lever or arm pivoted at the end of the cross head 23 beyond its point of pivotal attachment to the bracket 22 aforesaid, and 31 designates a stop flange or rib on the cross-head, adapted to stop and hold the lever 30 and its connections from further movement when the follower head 25 has reached a predetermined distance above the cutter carrying head 4, in order to prevent contact between and injury to the parts.
- 85 30 designates a lever or arm pivoted at the end of the cross head 23 beyond its point of pivotal attachment to the bracket 22 aforesaid, and 31 designates a stop flange or rib on the cross-head, adapted to stop and hold the lever 30 and its connections from further movement when the follower head 25 has reached a predetermined distance above the cutter carrying head 4, in order to prevent contact between and injury to the parts.
- 90 30 designates a lever or arm pivoted at the end of the cross head 23 beyond its point of pivotal attachment to the bracket 22 aforesaid, and 31 designates a stop flange or rib on the cross-head, adapted to stop and hold the lever 30 and its connections from further movement when the follower head 25 has reached a predetermined distance above the cutter carrying head 4, in order to prevent contact between and injury to the parts.
- 95 30 designates a lever or arm pivoted at the end of the cross head 23 beyond its point of pivotal attachment to the bracket 22 aforesaid, and 31 designates a stop flange or rib on the cross-head, adapted to stop and hold the lever 30 and its connections from further movement when the follower head 25 has reached a predetermined distance above the cutter carrying head 4, in order to prevent contact between and injury to the parts.
- 100 Having thus fully described my invention what I claim as new and desire to secure by Letters Patent is:—
1. In a slicing machine, a base plate formed with a central opening, a revoluble cutter carrying head arranged in said opening and provided with radially arranged cutter blades, means for supporting and revolving said head, a circular wall fixed to said base around said opening, a top for said wall comprising a fixed semi-circular top plate and hinged top plates of a quadrant shape, and a hopper open at top and bottom secured to said semi-circular top plate.
- 105 2. In a slicing machine, a base plate formed with a central opening, a revoluble cutter carrying head arranged in said opening and provided with radially arranged cutter blades, means for supporting and revolving said head, a circular wall fixed to said base around said opening, a top for said wall comprising a fixed top plate, a series of depending positioning pins secured to said circular wall and having engagement in orifices in the base plate, and a hopper open at top and bottom secured to said top plate.
- 110 3. In a slicing machine, a base plate formed with a central opening, a revoluble cutter carrying head arranged in said opening and provided with radially arranged cutter blades, means for supporting and revolving said head, a circular wall fixed to said base around said opening, a top for said wall comprising a fixed top plate, a series of depending positioning pins secured to said circular wall and having engagement in orifices in the base plate, and a hopper open at top and bottom secured to said top plate.
- 115 4. In a slicing machine, a base plate formed with a central opening, a revoluble cutter carrying head arranged in said opening and provided with radially arranged cutter blades, means for supporting and revolving said head, a circular wall fixed to said base around said opening, a top for said wall comprising a fixed top plate, a series of depending positioning pins secured to said circular wall and having engagement in orifices in the base plate, and a hopper open at top and bottom secured to said top plate.
- 120 5. In a slicing machine, a base plate formed with a central opening, a revoluble cutter carrying head arranged in said opening and provided with radially arranged cutter blades, means for supporting and revolving said head, a circular wall fixed to said base around said opening, a top for said wall comprising a fixed top plate, a series of depending positioning pins secured to said circular wall and having engagement in orifices in the base plate, and a hopper open at top and bottom secured to said top plate.
- 125 6. In a slicing machine, a base plate formed with a central opening, a revoluble cutter carrying head arranged in said opening and provided with radially arranged cutter blades, means for supporting and revolving said head, a circular wall fixed to said base around said opening, a top for said wall comprising a fixed top plate, a series of depending positioning pins secured to said circular wall and having engagement in orifices in the base plate, and a hopper open at top and bottom secured to said top plate.

Signed at Chicago, Illinois, this 1st day of June 1922.

MICHAEL KIRNBAUER.
